UNITED STATES PATENT OFFICE.

AMOS P. STEINER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA

GRINDING MACHINE.

Application filed June 20, 1924. Serial No. 721,292.

My said invention relates to grinding machines and it is an object thereof to provide a machine for grinding twist drills and other small cylindrical objects with a magazine feed which shall operate at predetermined intervals to discharge from the workholder the completed articles and replace them with articles to be ground.

Another object of the invention is to provide a fluid motor for operating the replenishing mechanism and means for setting the motor in operation at predetermined intervals.

Another object of the invention is to provide means for moving the grinding wheel toward and from the work during operation upon a single article.

Still another object is to provide means whereby the movement of a traversing carriage sets in operation the motor above referred to, reverses the fluid motor for the traversing carriage and actuates the means for moving the wheel toward and from the work.

Referring to the accompanying drawings which are made a part hereof and on which similar reference characters indicate similar parts,

Figure 1 is a front elevation of a machine embodying my improved mechanisms,

Figure 2, an end elevation of the same,

Figure 3, a detail of a cam shown in Figure 2,

Figure 4, a front elevation of the magazine operating motor with parts broken away for the sake of clearness, this figure and the remaining figures being on an enlarged scale,

Figure 5, a vertical section of said motor,

Figure 6, a vertical section of pawl and ratchet mechanism used in connection with said motor,

Figure 7, a plan view of the work centers, a work transferring slide and means for operating said parts,

Figure 8, an end elevation of the magazine, its motor and other auxiliary parts,

Figure 9, a front elevation of parts shown in Figure 7,

Figure 10, a composite end elevation of certain cams in Figure 8,

Figure 11, a much enlarged front elevation of a dog shown in Figure 1,

Figure 12, an elevation of parts shown in

Figure 10 looking at said figure from the right-hand side, and

Figure 13, a detail on a reduced scale of a part shown in Figure 11.

In the drawings reference character 20 indicates the frame of the machine which may be of any conventional or desirable form, being here shown as hollow and provided with suitable openings, doors, bearings, etc., all as is customary in machines of the same general character. An abrading device in the form of a wheel is illustrated at 21, said wheel being located on a shaft 22 carrying a pulley driven by a belt 23 passing over another pulley on the shaft 24 which is driven from any suitable source of power.

A traversing carriage is supported on the machine frame in front of the grinding wheel said carriage supporting a depending rack 25 (Figs. 1 and 2). A pinion 26 has teeth engaging those of the rack, said pinion being supported on a shaft 27 which also supports a fluid motor having a rotor whose actuating element is a vane 28. An inlet pipe 29 leads from a tank 30 to a pump dia-

grammatically illustrated at 31 said pump having a shaft 32 driven by a chain 33. From the pump the fluid under pressure is led by way of pipes 34 and 35 to valve mechanism including reversing devices operated by a reversing lever 36 and a pressure valve at 37 operating in connection with means hereafter described to slow down the traverse of the carriage. A pipe 38 carries the exhaust fluid back to the tank together with such fluid as may be by-passed from the pressure valve. A branch pipe 39 connects with the pipe 34 and this leads to a flexible pipe 40, the entrance to which is controlled by a valve 41 having an operating lever 42. The last-named pipe leads to a motor on the traversing carriage having a valve at 43 (Fig. 4) for controlling the entrance and exit passages. A flexible tube 44 leads from the last-named motor to a return pipe 45 by

which the pressure fluid is carried back to the tank, a pipe 46 also connecting therewith to return fluid by-passed from the casing of the valve 41. A valve 47 is provided for cutting off the flow of pressure-fluid to the carriage driving motor.

The traversing work carriage.

The traversing work carriage in addition

to the rack 25 carries a magazine 48 here shown as having an upwardly opening inclined chamber 49 which is long and narrow to accommodate objects 50 of a slender 5 cylindrical form, such as twist drills and similar objects. At its lower end the magazine is supplied with a guide 51 which is preferably resilient and underneath which the articles of work pass to the working position. At the other side of and approximately directly below the magazine is a lip 52 pivotally supported at 53 on a slide 54 said slide having a depending lug 55 located in opposed relation to a depending lug 56 on 10 the lip 52 between which lugs a secondary slide 57 is located, said slide having a lost motion connection with the depending lugs 55 and 56 whereby on forward movement of the secondary slide the upper slide is projected with the lip held up in the position shown in Figure 8 whereas on return movement of the secondary slide withdrawal of said slide from the lug 56 permits the lip to move about its pivots 53 into a position 15 to clear the work held in the work centers hereinafter described and thereafter by engagement with the lug 55 the secondary slide acts to retract the upper slide and the pivoted lip.

16 The secondary slide has a transverse notch at 58 in which is located the end of a rock-arm 59 fastened to a rockshaft 60, said shaft having another rockarm 61 bearing a pin 62 located in a laterally opening cam slot 20 63' of a cam 63.

21 A pair of work centers 64 and 65 are located in position to engage the twist drill or other similar piece of work shown at 66. One of said centers is in effect a swivel held 25 in a sleeve 67 movably positioned in a bearing 68, a spring 69 acting to hold it normally in the advanced position. The other center is surrounded by a sleeve 70 splined to a shaft 71 near its end. Said shaft is supported in suitable bearings and carries a 30 pulley 72. The sleeve 70 is forced toward the right to its advanced position by a spring 73 surrounding the shaft. The sleeve 70 has a slot in its forward end adapted to 35 receive the flat tang of a twist drill for driving the same, the sleeve thus providing what in effect is a chuck for the drill.

40 A pair of levers 74 and 75 are pivoted respectively at opposite sides of the magazine 48 and said levers are provided at their rear ends with rollers 76 and 77 acting as followers for cams 78 and 79 located on a shaft 80 which also has fixed thereto the cam 63 for actuating the slide by which articles of work 45 are carried from the magazine to the work-centers above described.

The work changing motor.

For driving the camshaft 80 which operates the work changing means consisting of 50

the means for separating and returning the work centers and the means for operating the slide 54 and its connected parts, I have provided a fluid motor shown in detail in Figures 4 and 5 and in a more general way 55 in Figures 1, 2 and 8. This motor comprises a casing or stator having a body 81 and end pieces 82 secured together in any convenient manner as by means of bolts or rivets 83. Within the housing thus formed there is a 60 rotor having a vane 84 connected in any convenient manner to the shaft 85. The movement of the rotor is limited by a block 86 to an oscillation of approximately 300°, said block extending from side to side of the 65 housing and being reduced at opposite sides to provide chambers communicating with passages 87 and 88 which in turn communicate with a valve chamber in which is located the valve 43. The valve chamber is 70 provided with an inlet pipe 89 and an outlet pipe 90 and it will be evident from consideration of the drawings that according to the position of the double-headed valve fluid under pressure will be admitted through one 75 or the other of passages 87 and 88 to drive the rotor in one direction or the other while at the same time an exhaust passage will be opened from the opposite side of the rotor through a passage 87 or 88 to the valve chamber and so to the exhaust pipe 90. The pipes 89 and 90 are connected respectively to the flexible tubes 40 and 44 (shown in Figure 1) so that the fluid from the tank 30 forced by the pump 31 through the tube 40 80 will be returned to the tank through the tube 44.

85 The shaft 85 near its righthand end supports a gear 91 loosely surrounding a ratchet 92 splined to said shaft. The gear has pivotally supported thereon adjacent to the ratchet a pawl 93 forced toward the ratchet by a spring 94. The gear 91 meshes with a gear 95 on the cam shaft 80 of the work changing mechanism and it will be evident 90 that the motor drives the work changing mechanism on its working stroke through the pawl and ratchet mechanism which working stroke is followed by an idle stroke in which the work changing mechanism remains stationary.

95 The valve 43 has a stem 96 projecting toward the left-hand end of the carriage and a head 97 on the stem. A coiled spring 98 is located between the head 97 and the cap 99 of a gland forming part of the valve casting so that the valve is normally held in its extreme left-hand position in which position of the valve the idle stroke of the motor takes place after which the rotor remains in the extreme opposite position to that shown 100 in Figure 5. A fixed abutment 100 is provided on the frame of the machine, said abutment being fixed to or integral with a rod slidably supported in an opening of a 105 110 115 120 125 130

post 101 and being adjustably secured in position by a set screw 102.

Wheel feeding means.

5 The grinding wheel 21 is provided with any conventional or desirable supporting means including provision for adjusting the wheel toward and from the work to compensate for the decrease in diameter of the 10 wheel due to wear. In addition to this a sliding cap 103 is provided by which the wheel is moved back and forth from the work in the operation of grinding each individual article of work. Preferably this 15 operation is performed step-by-step in synchronism with the stroke of the traversing work carriage so that as each stroke of the carriage is completed the wheel is advanced a distance corresponding to the reduction in 20 diameter of the work during a stroke of the carriage. For this purpose the cap is provided with one or more depending arms 104 provided with followers 105 coacting with a cam or cams 106. The cam is fixed to a 25 shaft 107 having at one end a beveled gear 108 meshing with a beveled gear 109 rigidly secured to a ratchet 110. A shaft 111 concentric with the ratchet has a rock arm supporting a pawl 112 engaging the ratchet 30 110. At its front end the shaft has another arm 113 adjustably connected to the reciprocating work carriage by abutments 114 located at opposite sides of the enlarged head of the rockarm and slidably adjustable 35 in a slot 115 of the carriage.

The machine here illustrated is arranged to grind a twist drill to the desired extent by four strokes (which number may be varied as desired) and as will be seen in Figure 3 the cam as here designed serves to control the wheel during the operation on two twist drills, said cam having two series of steps *a*, *b*, *c*, and *d* so formed that after step *d* the wheel is returned to its outermost 40 position by a relatively high and steep incline after which it may be moved step-by-step toward a position closer to the axis of the work by springs 116 arranged to act on lugs 117 depending from the cap so as to 45 force the cap and therefore the wheel toward the work. It will be seen that the springs act constantly to force the wheel toward its most advanced position which 50 action is opposed by the cams but this arrangement can be reversed if desired. Due 55 to the fact that the machine makes short strokes during which the pawl 112 feeds the ratchet only over a distance of one tooth (or a relatively small number of teeth) 60 whereas on the long strokes it would swing through a considerably larger arc and therefore feed the ratchet for a greater distance, it is important to provide means to prevent 65 the parts of the machine from getting out of time and for this purpose I have pro-

vided a shield 112' extending underneath the pawl and adapted to lift it out of engagement with the ratchet teeth on the long stroke, or otherwise expressed the shield limits the actual working stroke of the pawl 70 to a predetermined number of teeth which is uniform for both the long and the short strokes of the carriage.

Stroke controlling mechanism.

The operation of the machine is such that the table or carriage has two strokes of equal length followed by a long stroke which removes the work from the wheel and the workholders. During the long stroke the 80 completed work is removed and an unfinished article taken from the magazine is substituted therefor. A long stroke in the opposite direction then takes the carriage back to and through the working position, 85 the cycle thus consisting of a total of four strokes for each article which number may of course be varied as may be found desirable. For the purpose indicated and for other purposes the carriage is provided with 90 a pair of dogs 118 and 119 (Fig. 1), one of which is shown in an enlarged form in Figures 11 to 13. Each of the dogs is provided as usual with adjusting means consisting of a worm 120 engaging teeth on a rack bar 121 of well-known character on the front of the machine. The dog 119 is provided with a vertically slid able stop member 123 urged in one direction by a spring 124 and said stop member is adapted at its lower end to 95 engage with a block 125 on the reversing lever 36 for moving the valve of the carriage operating motor in one direction. At each stroke of the carriage toward the left a roller 126 on the dog engages a cam 127 100 fixed to the frame of the machine, said roller being mounted on a lever 128 pivoted at 129 and carrying at its free end a pivoted pawl 130 engaging with ratchet teeth 131 at the side of the stop member 123 which may appropriately be designated a ratchet bar. The rise of the cam is such that the pawl will lift the stop member only one tooth at each stroke. A detent pawl 132 pivoted at 132' 105 is forced toward the rack teeth by a spring 133. A similar spring 134 serves to force the pawl 130 toward said teeth.

A stop 135 is mounted on the dog 119 to the right of the stop 123 this stop serving to strike the block 125 and reverse the lever 36 when the stop 123 has been elevated so high as to miss said block or on the fourth stroke of the carriage for a piece of work. The stop is flattened at its lower end and has a head 136 at its upper end by which it may be lifted against the tension of the spring 137 if a still longer stroke of the carriage is desired, e. g. to move it out of the way of the grinding wheel as for repairs or resurfacing of the wheel.

After the stop 123 has been lifted to its full extent (as indicated in Figure 11) the carriage will make its long stroke whereby the parts are moved to the left into the position there shown. Near the end of this stroke a downward projection 138 on a lever 139 pivoted at 140 strikes a trip 141 fixed to the frame of the machine thereby swinging said lever in a counter-clockwise direction about its pivot. The lever has cam surfaces engaging pins 142 and 143 extending laterally from the respective pawls 130 and 132 and these cam surfaces act on the pins to disengage the pawls from the rack teeth 131, the lever 139 forming in effect a pawl lifter for disengaging said pawls, whereupon the spring 124 immediately forces the stop 123 downward. The downward movement is limited by bar or plate 144 of a height 20 to prevent the stop from engaging the block 125 on the next movement toward the right for which purpose in the present embodiment of the invention the bar is shown as having a cam incline to secure sufficient 25 height for the stop. On such stroke toward the right the tail end of the pawl lifter 145 strikes the trip 141 and so is caused to release the pawls 130 and 132 whereupon their springs 133 and 134 return them to active 30 position. The dog 119 carries also a cam bar 146 having oblique inclines at each end thereof said bar being secured in position by a set screw 147. As the cam moves toward the left with the carriage one of its 35 inclined surfaces engages a lever 148 for operating the valve 37 to diminish the supply of pressure fluid to the carriage reciprocating motor and thus retard the movement of the carriage. The bar has a horizontal surface 40 of substantial length between its ends so that when the carriage makes its long stroke to the left it will travel slowly during the excess movement toward the left and also during the return movement until it reaches the 45 position where ordinary grinding operation begins. A similar cam 149 on the other dog provides for retardation of the reciprocation as the carriage reaches the end of its stroke to the right.

50 Operation.

In the operation of my device the valves 41 and 47 being opened and the pump being set in operation fluid under pressure is admitted to the carriage reciprocating motor 55 for driving it in one direction or the other as the case may be. Thereupon the carriage moves for example toward the left carrying with it the magazine and other elements of the work replenishing mechanism, the dogs 60 118 and 119, the stops 114 etc., the rockarm 113 swinging to the left at this time and the pawl 112 riding freely over the ratchet teeth. Assuming the stroke to be of ordinary 65 nature the carriage will move until the lower end of the slide 123 engages block 125 and

reverses the position of the lever 36, this being the position illustrated in the drawings, the carriage slowing down as usual near the end of the stroke. The direction of movement of the carriage operating fluid motor is now reversed and the carriage moves toward the right whereupon the ratchet 110 is operated to move the cam 106 one step and permit the springs 116 to force the wheel one step nearer the work, which at this time is being rotated by the pulley 72. When the dog 118 approaches the lever 36 a lug at its lower end strikes the block 125 to reverse the lever, the cam 149 riding over the lever 148 to reduce the flow of pressure fluid as above explained and slacken the speed of the carriage as it approaches reversing position. This action continues for as many strokes as may be necessary according to the arrangement of the machine until the last stroke which completes the grinding operation on the article 66.

On the final stroke, the relative number of which is determined by the number of teeth 131 on the ratchet bar, the lower end of said bar has been raised so high that it passes over the block 125 and fails to reverse the lever 36. The cam 146 does, however, engage the lever 148 to slow down the travel of the carriage which preferably travels more and more slowly as it approaches the end of the stroke. This movement may be varied and the carriage may even stop at the end of the long stroke if necessary. The stroke continues until the stop 135 strikes the block on the reversing lever and forces it past central position after which springs or other devices well understood in the art throw it quickly toward extreme position. As the carriage approaches its extreme left-hand position the head 97 of the valve of the work replenishing fluid motor strikes the fixed abutment 100 and admits the fluid under pressure to the interior of the stator on the carriage whereupon the shaft 85 is revolved in the direction of its working stroke, operating the cam shaft 80 so that the cams 78 and 79 actuate levers 74 and 75 to withdraw the chuck 70 and the swivel support 65, it being understood that the cam 79 is preferably arranged to operate slightly in advance of the cam 78 though this is not essential. As the article 66 falls into whatever receptacle may be provided for it the slide 57 is being advanced carrying with it the slide 54 and lip 52 shown in the position in Figure 8 thereby transferring the lowermost article in the magazine to a position between the chuck and the swivel support. The cam 79 being slightly in advance of cam 78 the swivel 65 will contact with the work and carry it toward the center 64 whereupon the chuck 70 will engage the tang and rotate the work.

In the long traverse of the carriage the parts are moved so far that the swivel 65 is

in front of the grinding wheel, this leaving the space at the rear of the finished article free for the movement of said article when ejected, or free to receive means for receiving or carrying off such article. As the replenishing operation is completed the stop 135 will preferably have actuated the reversing lever and started the carriage in the opposite direction, it being understood that 10 the ratchet bar 123 has been released by engagement of the pawl lifter 139 with the stop 141, said pawl lifter being now returned to its original position to free the pawls by engagement of the tail thereof with trip 15 141 on the return movement. As the carriage moves to the right the head 97 is held against the abutment 100 by expansion of the spring 98 until the valve has moved far enough to reverse the connections of the passages 20 87 and 88 to the tubes 40 and 44 whereupon the fluid under pressure enters at the opposite side of the plate 84 and forces the rotor back on its idle stroke to its original position. The camshaft 80 has completed 25 its stroke during the working stroke of the motor and the slide 57 being retracted has first released the pivoted lip 52 to allow it to fall out of the way of the work between the centers and then has retracted the 30 slide 54.

During the actual grinding operation it will be understood that the grinding wheel which is now at its position farthest from the axis of the work will be returned step-by-step through the operation of the springs 35 116 and the cam 106 after which one of the high steps of the cam will move it again to its farthest position prior to work replenishment.

40 It will be obvious to those skilled in the art that my machine and the principle thereof may be changed in various ways without departing from the spirit of the invention and that it may be applied to various uses. 45 For example the wheel might be mounted on a traversing carriage, the magazine might be on the fixed frame and many other changes are obviously within the contemplation of the invention. Therefore I do not 50 limit myself to the specific embodiment shown in the drawings and described in the specification but only as indicated in the appended claims.

Having thus fully described my said invention, what I claim as new and desire to secure by Letters Patent is:

55 1. In a grinding machine, abrading means, work-holding means, a carriage for one of said means having traversing movement relatively to the other, a workholding magazine, means for successively feeding unfinished articles from the magazine to the workholding means, a fluid motor for operating said feeding means, and connections 60 whereby the traversing carriage sets the

motor in operation at predetermined times, substantially as set forth.

2. In a grinding machine, a rotary wheel, a workholder, a traversing carriage for the workholder, a magazine on the carriage, a fluid motor, a fixed abutment, and means on the carriage adapted to engage said abutment and thereby set the motor in operation to feed an object to the workholder, substantially as set forth. 75

3. In a grinding machine, a workholder, a magazine, a slide below the magazine adapted to carry the work to the holder, a pivoted work-supporting lip on the front end of the slide, means to support the lip positively on forward movement of the slide, said means being withdrawn on retraction of the slide to permit the lip to fall and clear the work, substantially as set forth. 80

4. In a grinding machine, work-centers movable toward and from each other, a magazine, a slide for carrying articles from the magazine to the work-centers, a pivoted work-supporting lip at the front of the slide, and means for successively separating the work-centers, advancing the slide, returning the work-centers, and retracting the slide including a camshaft and connections therefrom for supporting the lip positively during the advancing movement of the slide and permitting it to drop during the retracting movement, substantially as set forth. 85

5. In a grinding machine, work-centers movable toward and from each other, a magazine, a slide for carrying articles from the magazine to the work-centers, a pivoted work-supporting lip at the front of the slide, a camshaft, and connections from the same to the work-centers and the slide for successively separating the centers, advancing the slide, returning the centers, and retracting the slide, said connections including a lost motion connection for supporting the lip positively on its forward movement and releasing it on backward movement, substantially as set forth. 100

6. In a grinding machine, work-centers movable toward and from each other, a magazine, a slide for carrying articles from the magazine to the work-centers, a pivoted work-supporting lip at the front of the slide, a camshaft and connections from the same to the work-centers and the slide for successively separating the centers, advancing the slide, returning the centers, and retracting the slide, said connections including a lost motion connection for supporting the lip on its forward movement and releasing it on backward movement, a fluid motor 115

geared to the camshaft, and means for starting the motor after a predetermined grinding operation, substantially as set forth. 125

7. In a grinding machine, a grinding wheel, a traversing carriage, a fixed abutment, and devices on the carriage including 130

a workholder, a magazine, means for feeding articles from the magazine to the workholder, a fluid motor operating said means, and a valve for admitting fluid under pressure to said motor, said valve being operated by said abutment in a predetermined position of the carriage, substantially as set forth.

8. In a grinding machine, a grinding wheel, a traversing carriage, a fixed abutment, and devices on the carriage including a work holder, a magazine, means for feeding articles from the magazine to the work holder, means for separating the work holder to release a finished article and take up the articles supplied thereto by said feeding means, a fluid motor for operating said devices, and a valve for admitting fluid under pressure to said motor, said valve being operated by said abutment in a predetermined position of the carriage, substantially as set forth.

9. In a grinding machine, a grinding wheel, a traversing carriage, a fixed abutment, and devices on the carriage including a workholder, a magazine, a slide to carry articles from the magazine to the workholder, a pivoted lip at the front end of the slide, a fluid motor, connections from the motor for separating and returning the workholder and for reciprocating said slide, said connections including lost motion connections to said lip whereby it may fall away from the work when the slide is retracted, and a valve for admitting fluid under pressure to said motor, said valve being operated by said abutment in a predetermined position of the carriage, substantially as set forth.

10. In a grinding machine, a grinding wheel, a workholder, a traversing carriage for the workholder, a fluid motor for actuating the carriage, a fluid motor on the carriage, means actuated by the second motor for feeding articles to the workholder, and controlling means operated by the impact of the carriage for reversing the first-named motor and for placing the other motor in operation after a predetermined number of traversing movements, substantially as set forth.

11. In a grinding machine, a grinding wheel, a workholder, a traversing carriage for the workholder, a fluid motor for actuating the carriage, a fluid motor on the carriage, means actuated by the second motor for feeding articles to the workholder, controlling means operated by the impact of the carriage for reversing the first-named motor and for placing the other motor in operation after a predetermined number of traversing movements, means for moving the wheel toward the workholder step-by-step as the diameter of the work decreases and returning it prior to the next feeding operation, and

connections from the carriage for operating said means, substantially as set forth.

12. In a grinding machine, abrading means, a workholder, a carriage therefor, means for imparting to the carriage a series of uniform to-and-fro movements followed by a longer stroke in one direction, means on the carriage for feeding articles in succession to the workholder including a motor, and means actuated by the carriage on said longer stroke for starting the motor, substantially as set forth.

13. In a grinding machine, a rotary workholder, a rotary grinding wheel, a traversing table for one of said members, a base for the other adjustable toward and from the line of traverse of the table, a cap on the base, and ratchet operated by the traversing table, a cam moved by the ratchet, and a follower on the cap, said cam having high and low places arranged to separate the table and the wheel to the fullest extent at a single step while permitting them to approach step-by-step as the work is reduced, substantially as set forth.

14. In a grinding machine, a rotary workholder, a rotary grinding wheel, a traversing table for one of said members, a base for the other adjustable toward and from the line of traverse of the table, a cap on the base, means for moving the cap toward said line during the grinding of an article and retracting it after such operation including a cam, a follower on the cap, and means actuated by the table for moving the cam step-by-step, substantially as set forth.

15. In a grinding machine, a rotary workholder, a rotary grinding wheel, a traversing table for one of said members, a base for the other adjustable toward and from the line of traverse of the table, a cap on the base, means for moving the cap toward said line during the grinding of an article and retracting it after such operation including a rotary cam, a follower on the cap, a ratchet driving said cam, and a pawl therefor actuated by said table, substantially as set forth.

16. In a grinding machine, a traversing table, a fluid motor for driving the same, a reversing lever for the motor, a pair of opposed dogs on the table for operating said lever at the end of each traverse, and automatic means in connection with said dogs for producing a longer traverse after a predetermined number of strokes, substantially as set forth.

17. In a grinding machine, a traversing table, a fluid motor for driving the same, a reversing lever for the motor, a pair of opposed dogs on the table for operating said lever at the end of each traverse, and means in connection with said dogs whereby a longer traverse is permitted after a predetermined number of strokes, said means includ-

ing a third dog in position to reverse the lever at the end of such longer traverse, substantially as set forth.

18. In a grinding machine, a traversing carriage, a fluid motor for driving the same, a reversing lever for the motor, a pair of opposed dogs on the table for operating said lever at the end of each traverse, pawl and ratchet mechanism actuated to move the stop

10 on one of said dogs toward idle position on each stroke of a series thereby permitting a longer stroke at the end of the series, means for reversing the carriage after such longer stroke, and means to decelerate the 15 travel of the table during the excess portion of the stroke, substantially as set forth.

19. In a grinding machine, a traversing carriage, a fluid motor for driving the same, a reversing lever for the motor, a pair of opposed dogs on the table for operating said lever at the end of each traverse, one of said dogs comprising a slidable bar having a series of teeth, an actuating pawl for moving said bar to render the dog inoperative, a 25 detent to hold the bar, and automatic means for releasing the detent, substantially as set forth.

20. In a grinding machine, a traversing carriage, a fluid motor for driving the same, 30 a reversing lever for the motor, a pair of opposed dogs on the table for operating said lever at the end of each traverse, one of said dogs comprising a slidable bar having a series of teeth, an actuating pawl for moving said bar to render the dog inoperative, a 35 detent to hold the bar, and automatic means for releasing the detent, substantially as set forth.

21. In a grinding machine, a traversing carriage, a fluid motor for driving the same, 40 a reversing lever for the motor, a pair of opposed dogs on the table for operating said lever at the end of each traverse, one of said dogs comprising a slidable bar having a 45 series of teeth, an actuating pawl for mov-

ing said bar to render the dog inoperative, a detent pawl to hold the bar, a lifter for said pawls, means on the machine frame for actuating said lifter to release the pawls, and means also on the frame for returning 50 said lifter to idle position, substantially as set forth.

22. In a grinding machine, a traversing carriage, a reversing lever therefor, a dog on the carriage having a part for actuating 55 said lever, a fixed plate, means on the carriage engaging said plate on successive strokes of the carriage in one direction to move said part of the dog incrementally toward idle position, and means thereafter returning it to active position, substantially as set forth.

23. In a grinding machine, a grinding wheel, a traversing carriage for the work, 60 means for replenishing the work at intervals, means for lengthening the traverse of the carriage at intervals, pawl and ratchet mechanism operated by the carriage to move the grinding wheel toward and from the work between replenishing operations, and means 65 to interrupt the action of said mechanism during the excess portion of such lengthened traverses, substantially as set forth.

24. In a grinding machine, a grinding wheel, a traversing carriage for the work, 70 means for replenishing the work at intervals, means for lengthening the traverse of the carriage at intervals, pawl and ratchet mechanism operated by the carriage to move the grinding wheel toward and from the work between replenishing operations, and means 75 to lift said pawl during the excess portion of such lengthened traverses, substantially as set forth.

In witness whereof, I have hereunto set 80 my hand at Waynesboro, Pennsylvania, this 17th day of June, A. D. nineteen hundred and twenty-four.

AMOS P. STEINER.
